Primary Examiner — Darlington Ly

Assistant Examiner — Daniel J Domino

(57) CLAIM

The ornamental design for a craps table with proposition bet area layout, as shown and designed.

DESCRIPTION

FIG. 1 is a top plan view of a craps table with proposition bet area layout showing my new design; and,

FIG. 2 is an enlarged detail view of my design.

The broken lines showing a craps table is provided for the purposes of illustrating portions of the article and forms no part of the claimed design.

1 Claim, 2 Drawing Sheets
